UNITED STATES PATENT OFFICE.

FRANK O. ISAACSON AND EDWARD B. LEEFROM, OF KANSAS CITY, KANSAS.

WINDOW AWNING.

Application filed September 2, 1920. Serial No. 407,718.

To all whom it may concern:

Be it known that FRANK O. ISAACSON and EDWARD B. LEEFROM, citizens of the United States of America, residing at Kansas City, in the county of Wyandotte and State of Kansas, have invented new and useful Improvements in Window Awnings, of which the following is a specification.

The object of the invention is to provide a simple, inexpensive and efficient awning suitable for window and door openings, which shall have an increased durability in use as well as economical in construction and maintenance as compared with awnings as in the usual practice which employ canvas or awning cloth as the covering material, and furthermore to provide an awning of such construction as to adapt it without deterioration to be allowed to remain in position permanently as distinguished from those structures now in use which are removed or dismounted during the winter season and which, therefore, are subject to frequent handling in hanging and removing which serves to shorten the term of usefulness thereafter; and with these objects in view the invention consists in the construction and combination of parts of which a preferred embodiment is shown in the drawing, wherein:

Figure 1 is a view of the awning applied in the operative position to a window opening, the same being illustrated in its extended condition.

Figure 2 is a vertical sectional view of the same.

Figure 3 is a detail view of one of the awning sections or members.

The device consists essentially of a plurality of telescoping sector-shaped sections or members embodying the marginal members 10 and 11 and any desired number of intermediate sections or members 12, having the side wings 13 connected by common pivots 14, the marginal section 10 being adapted for rigid attachment by means of nails, screws or like fastening devices 15 to the casing 16 of the window or door. The sections are provided respectively at their inner or rear edges with the outwardly directed flanges 17 and at their outer edges with the inwardly directed flanges 18 to the end that the outwardly directed flange 17 of each intermediate and the free marginal sections 12 and 11 are adapted for engagement with the inwardly directed flanges 18 of the

adjoining sections or members, when the awning is extended to limit the relative movements thereof as will be obvious by reference to Figures 1 and 2. The outwardly directed flange 17 of the rear or stationary section or member being secured to the fixed support or casing of the window or door serves when the foldable sections or members are extended to maintain the awning in its operative position and said fixed section or member forms a housing for the foldable sections or members when the latter are collapsed or telescoped, such folding or telescoping movement being effected by means of operating cords 19 extending over a double pulley 20 at one side of the structure and a single pulley 21 at the opposite side thereof, the extremities of said cords being secured to lugs 22 on the outer marginal section or member 11, which together with the intermediate sections is provided on the front edges of the side wings with flanges 23. In the folding operation flanges 23 on the marginal section 11 engage the corresponding flanges on the next succeeding intermediate section and so on until all the sections are moved into telescoping position within the marginal section 10.

Each section or member is adapted to be struck from the single blank of sheet metal such as galvanized iron or the equivalent thereof which may be painted or otherwise coated as a protection from the water, to prevent rusting and the like, and the downward inclination of the transverse portion of the marginal or housing section or member 10 toward its outer edge serves to form a water shed when the awning is folded to protect the sections or members which are housed therein.

Having described the invention, what we claim as new and useful is:

A metallic awning consisting of a plurality of telescoping sector-shaped sections each having a transverse portion and side wings, the upper marginal member being formed with a continuous flange at the rear edge of the transverse portions and side wings and provided with holes by means of which the said section may be secured to a window frame, all of the remaining sections being formed with an outwardly extending flange at the rear edge of the transverse portion and the upper marginal section and all of the intermediate sections being formed with inwardly directed flanges at the for-

ward edge of the transverse portions, the lower marginal section and all the intermediate sections being formed with outwardly extending flanges on the side wings 5 at the forward edges of the latter, the inwardly extending flanges of the transverse portions engaging the outwardly extended flanges of adjacent transverse portions to maintain the awning in extended position, 10 the flanges on the side wings engaging the forward edges of adjacent wings to effect folding movement of the awning, and means terminally connected to the lower marginal portion by which it and all of the intermediate sections may be raised into forward 15 position.

In testimony whereof they affix their signatures.

FRANK O. ISAACSON.
EDWARD B. LEEFROM.
